[57] **CLAIM**

The ornamental design for a shroud lock for motorcycle handlebar controls, as shown and described.

DESCRIPTION

FIG. 1 is a top, rear, and right side perspective view of a shroud lock for motorcycle handlebar controls showing our new design;

FIG. 2 is an enlarged top, front, and left side perspective view thereof, shown in a slightly opened position;
FIG. 3 is an enlarged top, rear, and left side perspective view thereof, shown in an opened position; and,
FIG. 4 is an enlarged top, rear, and right side perspective view thereof, shown in an opened position.

The broken-line disclosure of portions of the handlebar and key in the views are for illustrative purposes only and form no part of the claimed design.
